(57) **CLAIM**

I claim the ornamental design for the carpet engaging vehicle container holder, as shown and described.

DESCRIPTION

FIG. 1 is a general perspective view of a carpet engaging vehicle container holder designed according to the present invention;

FIG. 2 is a general rear perspective view of a carpet engaging vehicle container holder designed according to the present invention;

FIG. 3 is a general rear perspective view of a carpet engaging vehicle container holder designed according to the present invention; and,

FIG. 4 is a general side perspective view of a carpet engaging vehicle container holder designed according to the present invention.

The broken lines immediately adjacent the shaded areas represent the bounds of the claim and all other broken lines are for illustrative purposes only. None of the broken lines form a part of the claimed design.
